PRESSER FOOT FOR SEWING MACHINES

Nathan L. Eudy, Wilmington, N. C.

Application April 3, 1943, Serial No. 481,707

3 Claims. (Cl. 112—139)

This invention relates to an improved presser foot for sewing machines by means of which a hem can be formed along one edge of a piece of cloth and one or more cords or strings can be incorporated within the hem.

More specifically, it relates to a presser foot mechanism, adapted to take the place of the conventional presser foot on a sewing machine, and comprising a shield having a hole therethrough for the needle to penetrate, and having a member disposed below the shield provided with an eyelet or hole therethrough for the string, cord, and the like to pass. The edge of the fabric is adapted to be folded around the eyelet member so that the hem will be formed with the string or cords therein. The eyelet member is pivoted so that when the presser bar of the sewing machine is raised, the eyelet member will drop downwardly towards the bed plate of the sewing machine so as to provide plenty of space between the shield and the eyelet member for the easy insertion of the strings through the eyelet in the eyelet member and also to facilitate the folding of the edge of the fabric therearound for the formation of the hem.

It is therefore an object of this invention to provide a presser foot for sewing machines having a shield portion and having a pivoted eyelet member disposed below the shield portion, and around which the edge of a fabric is adapted to be folded prior to sewing the two layers of the fabric together to form a hem, said eyelet member having a hole therethrough for the passage of cord, string, and the like to be incorporated within the hem by the sewing operation.

Some of the objects of the invention having been stated, other objects will appear as the description proceeds, when taken in connection with the accompanying drawing, in which—

Figure 1 is an isometric view of a portion of a sewing machine, showing my invention attached thereto;

Figure 2 is an elevation looking at the front end of Figure 1, and omitting the bed plate;

Figure 3 is a top plan view of the attachment, omitting all portions of the sewing machine;

Figure 4 is an elevation looking at the rear side of Figure 1, but showing the needle in lowered position, and showing the presser bar and guard 16 in raised position.

Referring more specifically to the drawing, the numeral 10 indicates a bed plate of a sewing machine having a suitable gate 11 whereby access may be gained to the bobbin compartment (not shown) of the sewing machine. The sewing ma-

chine has a conventional head 12 having a vertically movable presser bar 13 and a vertically reciprocable needle bar 14 which is adapted to hold a needle 15. To the lower end of the presser bar 13, my invention is adapted to be secured. The invention comprises a top shield portion 16, which is curved over and downwardly as at 17. This shield has an upstanding member 18, provided with a suitable slot 19 for the reception of a suitable screw or bolt 20, whereby the improved presser foot can be secured to the presser bar of the machine. The shield 16 has an opening 21 through which the needle is adapted to reciprocate in the sewing operation. In Figure 3, the needle opening 21 is shown somewhat closer to the cords in forming the hem than in Figures 1 and 2. This is shown for the reason that the mechanism can be made as desired to provide the upstanding member 18 and opening 21 in any desired position in the shield to thus form the line of stitches any desired distance from the folded edge 32 of the fabric 27. Pivotally secured to the lower portion of the upstanding member 18 is an arm 22 which curves outwardly and around in front of the front edge of the shield 16, and has secured thereto an eyelet member 23. The eyelet member has an eyelet 24 therethrough, through which suitable cords or strings 25 and 26 are adapted to be passed prior to a sewing operation. A piece of fabric 27 is adapted to be placed beneath the presser foot when the presser bar 13 has been raised upwardly, and this fabric is folded around the eyelet member 23, as shown in Figure 1. Then the presser bar 13 is lowered to sewing position, and the machine is started to form a row of stitches 30 in the fabric to form the hem in the edge of the piece of fabric. It is seen by observing Figure 2 that when the presser bar 13 is raised vertically, that the eyelet member will fall downwardly toward the bed plate of the machine to provide additional space for the easy insertion of the fabric around the eyelet member 23, and also greater room is provided for inserting the strings 25 and 26 through eyelet 24. Preferably the member 22 will rest against the top side of the shield 16 before the eyelet member touches the bed plate so as to thereby support the eyelet member a short distance above the bed plate when the presser bar 13 is in raised position, thus facilitating the insertion of the fabric 27 beneath the eyelet member and at the same time, enlarged space will be provided between the shield 16 and the eyelet member 23 to permit the fabric to be brought up around the

top of the eyelet member to a position as shown in Figure 1.

It is thus seen that I have provided a quickly attachable and detachable presser foot for sewing machines, which, on account of the pivoted eyelet member, provides easy access to the eyelet member and to the placing of the fabric beneath the shield and around the eyelet member prior to the sewing operation.

This invention can be employed in sewing continuous strips of material for the making of ordinary draw string tobacco bags, in which event the hem would be severed at the desired point to provide the desired width of tobacco bag, and the draw strings would be pulled out through the severed portion to cut them to a longer length than the width of the piece of fabric from which the bag was made.

In the drawing and specification there has been set forth a preferred embodiment of the invention, and although specific terms are employed, they are used in a generic and descriptive sense only and not for purposes of limitation, the scope of the invention being defined in the claims.

I claim:

1. In a presser foot for a sewing machine having a presser bar for forming a hem in one edge of a fabric and incorporating in said hem one or more cords, comprising a substantially concavo-convex shield having its concave side facing the bed plate of the sewing machine and extending to a point in front of the needle bar and needle of the machine and having a hole therein for reception of the needle, said shield having a vertically disposed portion for attachment to the presser bar of the machine, said shield having one edge extending downwardly in substantially vertical relation to the plane of the bed plate of the machine, an arm having its rear end pivoted for vertical swinging movement to the vertically disposed portion of the presser foot and extending forwardly and laterally of the shield and then inwardly towards the front edge of the shield, an eyelet member disposed beneath the front portion of the shield and being secured to the free end of the arm, said eyelet member having a hole therethrough extending from front

to rear of the eyelet member for the passage of one or more cords, the fabric being adapted to be disposed below said eyelet member with one edge thereof folded over the top of the eyelet member so that a line of stitches formed by the needle of the sewing machine will secure the two layers of fabric together while the cord or cords are disposed between the fabric and the edge folded over the top of the eyelet member.

2. In a presser foot for a sewing machine having a presser bar and a vertically reciprocable needle for forming a line of stitches in a fabric, a shield extending forwardly from the presser bar and to a point in front of the needle, and having a hole therein through which the needle reciprocates, said shield having a concave lower surface, an arm pivotally secured at the rear of the shield on a horizontal pivot, and extending outwardly and forwardly and inwardly, an eyelet member secured to the free end of the arm and disposed beneath the forward edge of the shield for vertical swinging movement on said horizontal pivot, said eyelet member having a hole passing longitudinally therethrough for the passage of a cord, the fabric being adapted to be placed beneath the eyelet member and one edge folded on top of the eyelet member so that the line of stitches formed by the needle will pass through both plies of the fabric to incorporate the cord in a hem formed by the line of stitches.
3. In a sewing machine having a presser foot and a needle, said presser foot having inner and outer means for forming a hem in one edge of the fabric, the inner means around which the fabric is folded having a hole therethrough for the passage of a cord to be incorporated into the hem, the inner means being pivotally mounted on a horizontal pivot on the rear of the outer means for vertical movement independent of the outer means so that when the outer means of the presser foot is raised, the inner means will remain in lowered position to provide greater space between the two fold forming means for the insertion of the fabric around the inner means.

NATHAN L. EUDY.
